[57] **CLAIM**

The ornamental design for a knife case, as shown and described.

DESCRIPTION

FIG. 1 is a perspective view of a knife case showing my new design;

FIG. 2 is an exploded perspective view with the cover removed;

FIG. 3 is a front elevational view with the cover removed;

FIG. 4 is a side elevational view taken in the direction of the arrows along line 4—4 in FIG. 3, the opposite side being a mirror image;

FIG. 5 is a sectional view taken in the direction of the arrows along line 5—5 in FIG. 3;

FIG. 6 is a sectional view taken in the direction of the arrows along line 6—6 in FIG. 3;

FIG. 7 is a top plan view of FIG. 3;

FIG. 8 is a rear elevational view of FIG. 3;

FIG. 9 is a bottom plan view of FIG. 3.

The views are drawn to a variety of scales for ease of illustration but are representative of only a single embodiment of the claimed design.
